CEMETERY HEADSTONE

Marian O'Leska, 521 Mitchell Ave.,
Clairton, Pa. 15025

Filed Jan. 22, 1971, Ser. No. 109,083

Term of patent 14 years

Int. Cl. D31

U.S. Cl. D79—2

The figure is a perspective view of the front portion of the cemetery headstone showing my new design as seen from the front and one side.

The rear not shown is plain.

I claim:

The ornamental design for a cemetery headstone, as shown and described.
